SHEET FEEDER

William Roy Hotchkiss, St. Paul, Minn.

Application June 24, 1933, Serial No. 677,479

8 Claims. (Cl. 271—53)

My invention relates to sheet feeding means which may be applied to a printing press, however, the principles and structure thereof may be equally applicable to other devices where it is desirable to feed sheets in the same manner. I have illustrated the sheet feeder associated with a lithographing cylinder and the accompanying parts to define the principles of the means which accomplish the desired results.

10 A feature resides in providing a sheet feeding means which is associated with sheet carrying means, stops, and gauge means, so that the sheet may be positioned to give an accurate registration as the sheet is carried from the feeding table to the lithographing cylinder.

15 In lithographing machines using a rotary cylinder, gripper fingers are provided which are carried by the cylinder and rotate with the same. These fingers grip the edge of the sheet fed to the cylinder, and owing to the fact that the rotary motion of the cylinder is comparatively rapid and is continuous, it is possible in transferring the sheet from the feeding bed to the cylinder, that the sheet may slip slightly and 20 get out of registry, preventing an accurately defined impression and making it difficult to make a perfect registration of the sheets, even though the sheet has been definitely and perfectly registered on the table. The sheets are 25 usually carried from the stack by feeding means onto a table which has a conveyor adapted to carry the sheets up to the impression cylinder. The sheets are accurately registered on the table prior to being fed to the gripping fingers of the 30 cylinder, and it is essential that this registry be maintained on the cylinder to give an accurate impression or printing of the sheets. I accomplish this by providing the necessary 35 means for registering the sheets on the registry table and for carrying the sheets therefrom into accurate and positive registration on the impression cylinder, preventing any possible slipping of the sheet out of registry before it is 40 positively engaged by the gripping fingers of the impression cylinder.

45 It is also a feature to provide means for engaging the registered sheet and over-feeding it to stops adjacent the engaging ends of the gripping fingers, so that the sheet is actually fed against the registering stops associated with the gripping fingers of the cylinder and not just picked up by the fingers and carried onto the impression cylinder. My over-feed means has an outstanding advantage of insuring the holding 50 of the sheet into registry and forcing it into

position, whereby it is positively engaged by the gripping fingers uniformly and in accurate registered position so that there is no chance of the sheet getting out of registry between the table and cylinder. My over-feed means drives the sheet with a little more extra force or speed than would be necessary to just time the movement of the sheet with the movement of the gripping fingers of the impression cylinder, thus causing the sheet to bow slightly adjacent the over-feeders as the edge of the sheet strikes the stops at the gripping fingers and then the over-feed means does not release the sheet until after the gripping fingers have positively engaged the same, whereupon the over-feed is released and is inoperative until it is time to engage the next sheet in the same manner.

55 It is also a feature to provide guide means extending around the cylinder with slots through which the edges of the gripping fingers may pass while they are in their open position projecting from the cylinder. This guide means holds the forward edge of the sheet so as to bring the same into perfect alignment with the stops adjacent the gripping fingers on the cylinder.

20 I also provide means for preventing any back-lashing in the over-feed means so that a positive and accurate registration is obtained with my rotary over-feeding means and the rotating 25 impression cylinder.

30 In the drawings forming part of this specification:

35 Figure 1 is a diagrammatic plan view of a portion of a lithographing press, illustrating the sheet registry table and showing my over-feeding means associated therewith to feed the sheets to the cylinder of the press.

40 Figure 2 is a diagrammatic side view of the left-hand side of the same.

45 Figure 3 is a detail portion of the same.

Figure 4 is a small sectional view through the impression cylinder, showing the gripper cam in dotted outline, and arm for operating the gripping fingers by the cam.

50 Figure 5 is an enlarged diagrammatic sectional detail on the line 5—5 of Figure 1.

Figure 6 is a diagrammatic section of a portion of the associated parts similar to the section of Figure 5, showing the over-feeding of the sheet 55 to the impression cylinder.

Figure 7 is a diagrammatic detail of the Geneva feeding means.

Figure 8 is a detail showing the brake on the 55

shaft operating the over-feeding rolls to overcome back-lashing.

The press A which is provided with the impression cylinder B is only partially illustrated 5 to show the associated parts with which my sheet feeder C operates. The press A is provided with a sheet feeding and registering table 10. Conveyors 11 operate in the bed of the table 10. These conveyors incline toward the 10 longitudinal feed gauge D and carry the sheet in the direction of the arrow in Figure 1, along the table 10 under the balls 12 which are carried in the outer ends of the adjustable brackets 13 which are positioned above the conveyors 11 15 so that the balls 12 will tend to hold the sheets bearing against the conveyors 11. The sheets E are carried onto the table 10 by any suitable sheet feeding means which operates intermittently to feed the sheets onto the table and to 20 the conveyors 11 and which is not shown in the drawings.

My sheet feeder C is formed with over-feeding wheels 14 which may be rubber-faced, or of any suitable material, so as to readily engage the 25 sheets E at the proper time to feed them in the manner as will be pointed out. The wheels 14 are carried upon the shaft 15 which is held by the brackets 16 to the transverse shaft 17. The ends of the shaft 17 are mounted to the frame 30 of the press A. The brackets 16 hold the shaft 15 so that the wheels 14 may be raised and lowered intermittently. The shaft 17 is limited in turning to move the wheels 14 down toward the under wheels 14' by an adjustable bracket 35 18 which carries an adjusting screw 19 in the free end of the same, acting as a stop to prevent the shaft 17 turning beyond the limits of the setting of the stop screw 19, and thus regulating the downward movement of the wheels 14 toward the under wheels 14'. The under wheels 40 14' are mounted on the shaft 60 of the mechanism F. The under wheels 14' are directly below the wheels 14 and co-operate therewith to feed the sheets in the feeder C.

The sheet feeder C is provided with a sheet 45 guiding plate 20 which extends above the table 10 to form the sheet guiding space 21 between the table 10 and the plate 20, and the forward end 22 of the plate extends closely thereto so as to guide the forward edge of the sheet E. A recess 23 adjacent the wheels 14 is formed in the under surface of the plate 20 so as to permit the sheets E to raise slightly when they are over-fed to the cylinder B.

The forward edge of the sheet E is caused to 55 engage stop pins 24 carried by the shaft 25 when the sheet E is brought into registry upon the table 10. These pins project toward the table 10 and act to register the front edge of the sheet and to stop the sheet from forward movement on the table 10 while it is being registered. The shaft 25 rotates to carry the pins into the position illustrated in Figures 5 and 6 after the sheet has been registered on the table 10 and when the over-feeder C operates to feed the sheet E to the gripping fingers 26 of the cylinder B.

Adjacent the shaft 25 and the pins 24, I provide a fixed sheet guide 27 which has a sheet guiding skirt 28 which curves around the shaft 70 25 and is slotted to permit the pins 24 to rotate into and out of sheet stopping position. The pins 24 rotate out of stopping position in the direction of travel of the sheet E. The guide 27 has an arcuated under surface 29 which fits

closely to the end of the table 10 over which it lies and over the cylinder B, as illustrated in Figures 5 and 6. This arcuated surface 29 provides a guide for the forward end of the sheet E as it is driven by the over-feed wheels 14 to the gripping fingers 26. The guide 27 is formed with arcuated slots 30 cut into the arcuated surface 29 which permits the free gripping ends 26' of the fingers 26 to pass through the same while in open position. As the impression cylinder B rotates, carrying the fingers into the slots 30, the fingers 26 are opened and while in these slots the forward edge of the sheet which has been registered against the pins 24, is driven from this position by the over-feeder wheels 14 and the under feeder wheels 14' against the stops 31. The fingers 26 then close down onto the edge of the sheet E before the fingers are out of the slots 30 and while the edge of the sheet is held under the arcuated 10 guidance surface 29. The guide 27 provides a means of holding the forward edge of the sheet E so that it may be driven against the stops 31 and under the ends 26' with sufficient force to insure registry of the sheet E on the cylinder B. 15 While the sheet is driven up in this manner it is held firmly by the engagement of the wheels 14 and 14'. Thus the sheet cannot possibly skew-gee or slip out of registry and is therefore carried to the impression cylinder B in perfect 20 registry.

The over-feeding sheet means C is operated by the lever 32, one end of which is secured to the shaft 17 and the other end is urged by the spring 33 to tend to rotate the shaft 17 in a manner to 25 cause the arm 16 to bear down on the shaft 15 and in turn move the wheels 14 toward the table 10. However, the cam arm 34, one end of which is secured to the shaft 17, and the other end of which engages the intermittent motion 35 cam 35, normally holds the over-feed wheels 14 out of operative position to engage the sheet E coming along in registering position on the table 10. The shaft 15 is connected by the gear 36 to the driving gear 37 which operates on the 40 shaft 38, and the gear 37 is adapted to be intermittently operated by the Geneva mechanism F. The Geneva mechanism is of the usual form with the intermittent motion wheel 39 and the Geneva drive wheel 40, illustrated in Figure 7. 50 The drive wheel 40 is driven by the shaft 41 of the press A in any suitable manner, not illustrated.

The Geneva mechanism F is intermittently operated to rotate the over-drive feeding wheels 55 14 and the wheels 14' after the sheet E has been registered on the table 10 with its forward edge stopped against the pins 24. Then the intermittent motion cam 35 operates to drop the wheels 14 into engagement with the sheet 60 E to firmly engage and hold the sheet against moving out of registry, after which the pins 24 are rotated by the lever means 42 which is lifted by the cam roller 43 traveling upon the stop cam 44, and subsequent to this operation 65 the Geneva mechanism F starts to rotate the wheels 14 and 14' through the gears 36 and 37. The rotation of the over-drive wheels 14 and the under-drive wheels 14' forces the sheet E against the stops 31, as hereinbefore set forth, 70 while the ends 26' are in open position in the slots 30. The wheels 14 and 14' operate fast enough to provide a slightly greater impulse to the sheet E than would be necessary to bring it into direct time with the movement of the 75

cylinder B. The front end of the sheet E is held under the guide 27 so that it cannot buckle or twist. The over-driving of the wheels 14 and 14' causes the sheet to bulge up slightly into the recess 23 of the guide 29, and the fingers 26 positively grip the front end of the sheet E, securing it in perfect registry to the cylinder B, after which the cam 35 raises the arm 34, which in turn raises the wheels 14, and the Geneva mechanism stops the rotation thereof.

The gears 36 and 37 do not disengage but are moved slightly apart out of their pitch engagement. To maintain the shaft 15 in perfect registry operation, I provide an adjustable brake 45 which is formed with an adjusting screw 46 and gripping shoes 47 to adjust the tension on the shaft 15 and thereby overcome any back-lashing and preventing any change in the registering operation of the mechanism C.

The degree of pressure of the wheels against the sheet E is regulated by the stop 18 so that more or less engagement may be provided, according to the adjustment of the screw 19.

When the sheet E is engaged by the grippers 26, it is carried around the cylinder B in accurate registration thereon. There has been no chance for the sheet to slip or lag and, therefore, it is in positive registration. The sheet E is released from the grippers 26 at the proper time when the shoe fly levers 48 operate to cause the ejecting pins 49 to release the sheet from the ends 26'.

It will therefore be apparent that I provide a means of feeding sheets to the impression cylinder B, maintaining them in perfect registry at all times and preventing any possible chance of the sheets lagging in relation to the impression cylinder B in the movement thereof, even though the condition of the paper may vary, owing to the atmospheric conditions. Thus the sheet cannot slip out of registry in being transferred from the feeding table to the impression cylinder. The wheels 14 and 14' give two distinct points of engagement to more securely hold the sheet. It is also evident that my feeding means may be applied to other devices where a feeder of this character is desired, other than presses, while the essential accomplishments in relation to a lithographing press evidence the outstanding merit of the same.

The illustrations are only suggestive of a means of carrying out the principles of the invention which should be considered within the scope of the claims to provide the broadest interpretation thereof.

I claim:

1. A sheet booster for printing presses including, a series of resilient tired wheels, means for holding said wheels inoperative, preliminary side and front sheet registering means associated with said wheels, a Geneva mechanism for intermittently operating said wheels, a gear back lash preventing brake therein, means for causing said wheels to engage the sheet before rotation of the same, and means for releasing the wheels from the sheet after it has been boosted by said wheels into printing position.

2. A sheet engaging and feeding means for rotary printing presses including, resiliently tired sheet engaging wheels, means for normally holding said wheels out of engagement with the sheet while it is registered, means providing a preliminary side and front registry for the sheet, means for moving said wheels into en-

gagement with the sheet after it is registered and while said wheels are not rotating, means releasing said sheet registering means, a Geneva operated means for rotating said wheels to drive the sheet to registering position on the printing cylinder, a gear back lash preventing brake therein, and sheet guiding means associated with the cylinder and the grippers thereof to guide the forward end of the sheet into registering position so as to be engaged by the grippers while the body of the sheet is fed with a higher speed to over-feed the same to the gripping means of the cylinder, and means for releasing said driving wheels when the cylinder gripping fingers have positively engaged the same.

3. A sheet feeding device including, a rotatable lithographing cylinder, grippers on said cylinder, and means for over-feeding a sheet to said grippers including, a registering stop, a pair of cylindrical rollers engageable with the sheet registered by said stop, and means for rotating said rollers with a gradually increasing and decreasing speed, said rotation being started before said stops are released for feeding said sheet to said grippers including a pair of discs, a pin on one rotatable disc engageable in slots in the other disc to impart intermittent motion thereto, and means cooperating between the discs to hold said other disc motionless between engagements, means for releasing said stop upon engagement of the sheet by said rollers, and means for holding said rollers against said sheet until said sheet is engaged by said grippers.

4. A sheet feeding device comprising, a rotatable cylinder, means for feeding sheets to said cylinder including, a pair of rollers spaced apart, registering stops, means releasing said stops after movement of said rollers has started, means for moving said rollers together into contact with opposite sides of a sheet, means for rotating said rollers with a gradually increasing and gradually decreasing speed including a pair of discs, one of said discs being rotatable, a pin on said one disc, grooves on the other disc cooperable with said pin to rotate said other disc intermittently, and means cooperable with said discs to hold said other disc from rotation between intermittent movements thereof, and means for spacing said rollers after said sheet has been received by said cylinder.

5. A sheet feeding means including, a rotary cylinder, grippers thereon, and a mechanism for feeding sheets thereto including, a cylindrical lower sheet engaging roller, a rockably mounted cylindrical upper sheet engaging roller cooperable with said lower roller to engage a sheet therebetween, registering stops, means releasing said stops after said rollers start in motion, a cam for rocking said upper roller into and out of engaging position, said cam moving said upper roller out of engagement with said sheet after said sheet is engaged by said grippers, and means for intermittently operating said rollers in unison.

6. A sheet feeding device including a feeding table, a pair of spaced feeding members for feeding a sheet on said table, means for moving said feeding members together to engage a sheet, stop means for holding said sheets in registered position, a longitudinally extending fixed guide member suspended above said table, an end on said guide member extending adjacent said stop means and slightly spaced from said table to guide said sheets against said table adjacent said stop, and a cut away portion in said guide

member between said end and said feeding members to accommodate a bulge in the fed sheet between the stop means and the feeding means.

7. A sheet feeding device comprising stop means for registering a sheet, relatively movably mounted pairs of feed rollers, means for moving said rollers of each pair together to engage a sheet, means for rotating said rollers, and means for releasing said stop means after movement of said sheet by said feed rollers has started.

8. A sheet feeding device comprising a cylinder, grippers thereon, a feed table, registering stops on said table for registering a sheet, feed rollers engageable and disengageable with said sheet, means for rotating said feed rollers, and means for releasing said registering stops after said sheet has been moved by said feed rollers causing a bulge in said sheet to the rear of said registering stops.
